[57] **CLAIM**

The ornamental design for a housing for a telephone handset, as shown.

DESCRIPTION

FIG. 1 is a perspective view of a housing for a telephone handset, showing my new design;

FIG. 2 is a top plan view thereof;

FIG. 3 is a side elevation thereof, the opposite side being a mirror image of the side shown; and

FIG. 4 is a front elevation thereof.

FIG. 1

FIG. 2

FIG. 3

FIG. 4
